US0D1099515S

(12) **United States Design Patent** (10) **Patent No.:** **US D1,099,515 S**
(45) **Date of Patent:** **** Oct. 28, 2025**

(54) **SILICONE BALL**

(71) Applicant: **Ningbo Gecen Promotion & Gift Co., Ltd.**, Zhejiang (CN)

(72) Inventor: **Weijin Ying**, Zhejiang (CN)

(**) Term: **15 Years**

(21) Appl. No.: **29/971,561**

(22) Filed: **Nov. 4, 2024**

(51) LOC (15) Cl. **03-01**

(52) U.S. Cl.

USPC **D3/207**

(58) **Field of Classification Search**

USPC D3/201, 207–212, 215, 217, 218, 228,
D3/229, 245, 246, 254, 259, 273, 274,

(57) **CLAIM**

The ornamental design for a silicone ball, as shown and described.

DESCRIPTION

FIG. 1 is a front and top perspective view of a silicone ball showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a rear and bottom perspective view thereof.

1 Claim, 8 Drawing Sheets
